VICTOR A. LILLQUIST, OF SUPERIOR, WISCONSIN.

RAILROAD-CROSSING GATE.

1,254,611.

Specification of Letters Patent. Patented Jan. 22, 1918.

Application filed April 24, 1917. Serial No. 164,195.

To all whom it may concern:

Be it known that I, VICTOR A. LILLQUIST, a citizen of the United States, residing at Superior, in the county of Douglas and State 5 of Wisconsin, have invented new and useful Improvements in Railroad-Crossing Gates, of which the following is a specification.

This invention relates to gates, and more especially to those which are mechanically 10 operated by a passing train and automatically returned to their housed position; and the object of the same is to produce a gate for points where the highway crosses a railroad track or tracks, which will provide both 15 a barrier and a signal against the approaching vehicle or pedestrian.

The invention consists of the gate-operating mechanism actuated by impact of a cam on the bearing of the front axle beneath a 20 locomotive or electric car and the details are set forth in the following specification, reference being had to the drawings wherein:—

Figure 1 is a side elevation of this structure at one side of a highway-crossing (the 25 latter indicated by the letter C) showing the gate as raised in full lines and lowered in dotted lines and diagrammatically indicating an approaching wheel and its cam.

Fig. 2 is a cross-section on the line 2—2 30 of Fig. 1, carried through only one rail of the track and showing the gate as raised.

Fig. 3 is a cross section on about the same line, showing the gate as lowered and illustrating how a platform may be built as 35 an approach to the rail, and between the rails and how a plate may be employed to protect the gate from dirt.

Fig. 4 is a perspective detail showing the engagement of the spring with the finger.

In conjunction with this invention it is 40 necessary to illustrate only one rail R and its web W, and to diagrammatically show the tread T and the flange F of a wheel and the bearing B for its axle, the bearing in this 45 case being inside the flange. While I speak of the element B as a bearing, it may be anything carried by and depending beneath the axle inside the flange, but this is immaterial.

Coming now to the invention proper, the 50 gate comprises upright straps 1 and 2, connected by horizontal slats 3 and 4 pivoted at their ends to said straps and therefore always maintained in parallelism, and one of said slats may carry a sign as indicated at 55 5, and possibly an electric lamp as indicated at 6, the wiring for which is not necessary

of illustration in this case. I might add that the gate could carry an audible signal such as bell which is sounded when the gate is raised, but these details also are not necessary for illustration. The straps 1 and 2 extend down past the ball of the rail alongside its web W and are pivotally connected therewith at points 11 and 12 on the inner or flange side of the rail, the strap 2 being continued beyond its pivot in an arm 8 which moves beneath a spring 9 when the gate rises, so that the latter is thereby held frictionally in elevated position. At other times the arm slips from contact with the spring and the gate folds down past the ball of the rail alongside its web and completely out of sight, thus housing the sign, the bulb, and the audible signal. In Fig. 3 a platform 13 is shown built as an approach to the rail and continued as at 14 between the rails. On the outer side of the rail in question this platform may be built completely up to the ball of the rail, but on the inner or flange side of the rail the platform 14 is spaced therefrom so as to leave a channel 15 within which the gate is housed when it is folded down, and this channel may be wholly or partly covered by a plate 16 having one edge downturned and mounted on a beam 17 in 80 the platform and its other edge projecting toward the rail but spaced a sufficient distance therefrom to permit the rise of the gate. This plate prevents the possibility that a horse may get his hoof into the channel for the wheel-flange, and obviously keeps much dirt out of the channel 15 which might otherwise interfere with the gate structure. It is to be understood that I am describing and illustrating herein only the 85 gate which stands adjacent one rail and is operated by a train or engine approaching from the right in Fig. 1, but there is to be a similar gate on the other rail operated by a train approaching from the other direction, or if there are two tracks this additional gate will be on the appropriate rail of the second track so that a train approaching from the left will set it in a manner yet to be described.

The actuating mechanism for the gate thus described consists of a rod 20 pivotally connected at 21 with the lower end of the arm 8 and with the lower ends of several links 22 and 23, and the rod is of such length that it extends from the channel 15 along the flange side of the rail for a considerable

distance from the highway indicated by the letter C as referred to above. The outer end of the rod is preferably turned obliquely upward as at 24, passed loosely through a guide 25, and provided at its extremity with a head 26 which lies alongside the ball of the rail R; and the innermost link 22 is continued upward past its pivot into a finger 27 which also lies alongside the ball 10 of the rail. It is to be understood that this finger stands quite near the gate, but the rod is of ample length so that its headed outer end stands at a considerable distance from the crossing C and the gate—perhaps 15 a hundred or two hundred yards.

When now a train approaches from the right in Fig. 1, a cam 100 which is mounted beneath the bearing B inside the flange F of its front right wheel, strikes the head 26 20 which is projected slightly above the rail R when the gate is closed. The impact pushes the inclined end 24 obliquely downward through the guide 25, and swings the rod on its several links. Movement of the link 22 25 raises its finger 27. Movement of the arm 8 raises the strip 2, and this through the connecting slats 3 and 4 raises the other strip 1 so that the entire gate rises out of the channel 15 and stands directly across 30 the roadway or crossing C, and thus an approaching pedestrian or driver has full notice that a train is coming. The latter proceeds on its way and finally the cam 100 strikes the finger 27 of the link 22. This 35 rocks said link on its pivot with the result that the rod 20 is moved in the opposite direction to fold the gate down into the channel 15 and to raise the oblique end 24 and set the head 26 for impact by the cam 40 on the next succeeding train. Thus an approaching train first sets the gate, and then, just before reaching the gate, it trips the same or folds it down into the channel 15, past the plate 16 if the latter be employed, 45 and out of the way of the flange F of the wheel which runs along the inner edge of said plate and over the crossing C. Lest the impact should raise the gate too high, I mount the spring 9 on a pin 29 in the web 50 W at such point that the arm 8 strikes this pin when the strip 2 is vertical, and lest the folding of the gate should carry it too low I provide another pin 30 against which this strip strikes when the gate is housed within 55 the channel 15. These pins therefore constitute stops to limit the rising and descend-

ing movements of the gate. The platform structure protects the gate from interference by malicious persons or from contact by the wheel of a passing vehicle or the 60 hoof of a passing animal, but except at the crossing C there is hardly necessity for protecting the rod and the links as all parts are of metal and lie close inside the rail so that the latter in effect protects them. The outer 65 end of the rod 24 is preferably made flexible so that if the locomotive in backing should cause the cam 100 to strike this end, the latter will spring downward and no harm will 70 result.

What is claimed as new is:—

1. In a railroad crossing, the combination with upright strips adapted to be pivoted at their lower ends to the web of the rail at the highway crossing, parallel slats pivotally connecting said strips and constituting the gate body, an arm projecting rigidly from the lower end of one of said strips and deflected out of line therewith, and a spring for frictionally engaging and holding said arm when the gate rises; of a rod pivotally connected with the lower end of said arm and leading along the flange side of the rail in the direction of an approaching train, links pivotally connecting this rod 85 with the rail-web, a gate opening finger rising rigidly from the link nearest the gate alongside the ball of the rail, and a contact head at the outer end of the rod, for the purpose set forth. 90

2. In a railroad crossing, the combination with strips adapted to be pivoted at their lower ends to the web of the rail at the highway crossing, slats connecting said strips and constituting the gate body, an 95 arm projecting rigidly from the lower end of one of said strips, and a spring for frictionally engaging and holding said arm when the gate rises; of a rod pivotally connected with said arm and extending along 100 the flange side of said rail in the direction of an approaching train, its outer end being bent obliquely upward and provided with a head at its extremity adapted to be projected above the ball of the rail, a guide 105 through which the oblique end is slidably mounted, and a gate opening finger pivoted to the rod and to the rail adjacent the gate and raised alongside said rail when the gate is raised, for the purpose set forth. 110

In testimony whereof I affix my signature.
VICTOR A. LILLQUIST.
